UNITED STATES PATENT OFFICE.

JOHN H. DAVIS, OF CHICAGO, ILLINOIS, ASSIGNOR TO CHARLES O. HADLY, OF PHILADELPHIA, PENNSYLVANIA.

CHECK-PERFORATING MACHINE.

Application filed February 1, 1927. Serial No. 165,108.

This invention relates to check perforating machines and the principal object of the invention is to provide a novel check-perforating machine provided with a plurality of 5 parallel rows of movable tapes, each tape carrying a plurality of lettered plungers for operating perforating punches vertically reciprocably mounted in the frame to perforate a check placed in the machine, the tapes being 10 collectively or individually movable to shift the lettered plungers, whereby the location of the perforations in the check for each setting of the tapes will differ.

Other objects of the invention are to provide 15 novel means for individually adjusting the tapes; means for locking and unlocking the tape rollers from the setting drum; and means for clamping the check blank in the machine prior to perforating same.

20 Other minor objects of the invention will be hereinafter set forth.

I will explain the invention with reference to the accompanying drawings which illustrate one practical embodiment thereof 25 to enable others to adopt the same; and will summarize in the claims the essentials of the invention, the novel features of construction, and the novel combinations of parts, for which protection is desired.

30 In the drawings:

Fig. 1 is a top plan view of the machine.

Fig. 2 is a side elevation thereof.

Fig. 3 is a section on the line 3—3, Fig. 1.

35 Fig. 4 is a detail of the stationary plungers for perforating the check.

Fig. 5 is a detail of a modified form of tape.

Fig. 6 is an enlarged plan view showing the mechanisms for collectively and individually adjusting the tapes.

Fig. 7 is a section on the line 7—7, Fig. 6.

40 Fig. 8 is a section on the line 8—8, Fig. 6.

Fig. 9 shows a check filled out and perforated by the machine for one particular setting of the tapes.

45 Fig. 10 shows a key board corresponding with the one particular setting of the tapes, by which the check when superimposed thereon may be verified.

As shown in the drawings my novel machine 50 comprises a base 1, having a recess 1^a in its upper face adapted to receive a plate 2, said recess being slightly deeper than the thickness of plate 2. Above base 1 is a plate 3, fixedly mounted upon the base 1 at the ends thereof; and above the plate 3 is a plate

4, covering the entire area of plate 3, but preferably spaced therefrom as shown in Fig. 3. Plates 2, 3, and 4 are provided with groups of registering bores or perforations 2^a, 3^a, and 4^a as hereinafter set forth, for the reception of check perforating punches hereinafter described.

In each corner of recess 1^a is a post 1^b having its ends fixed in the plates 1 and 3, said posts slidably engaging perforations in the corners of plate 2, to prevent removal of plate 2 from the machine while permitting plate 2 to be raised and lowered in the recess 1^a. In base 1, below plate 2, is mounted a shaft 1^c carrying cams 1^d whereby when the shaft 1^c is rocked by turning knob 1^e, the plate 2 will be raised so that its upper face is brought into contact with the lower face of plate 3 to clamp the blank check C between plates 2 and 3.

Plates 2, 3 and 4 at the rear end of the machine are provided with two substantially semi-circular recesses 4^b, which expose the underlying upper portion of the movable plate 2, said recesses facilitating the entry and removal of the blank check C (Fig. 9) 50 into and out of the machine, which check C is inserted from the rear end of the machine between suitable guides (not shown) between the plates 2 and 3, while plate 2 is in lowered position. The outer edge of check C may be adjusted to a base line 2^c marked upon the exposed portion of the upper face of plate 2, whereby a number of checks C 55 may be successively centered in the machine, each check successively occupying the same position in the machine between plates 2 and 3.

The registering bores or perforations in the plates 2, 3, and 4 are grouped as follows (see Fig. 10), the groups all lying within the area of the check C when same is inserted in punching position in the machine. At the front end of the machine is a group A consisting of four parallel rows of aligned bores adapted to extend across the full width of check C at the bottom thereof, there being twenty-six such registering bores in each row, corresponding to the number of letters in the alphabet, each registering bore carrying a check perforating punch hereinafter described; and shifting or movable operating plungers mounted on tapes are provided above plate 4 for depressing said punches.

In rear of group A is a group B of reg. 110

istering perforations, said group being disposed at approximately the center of check C, and consisting of nine parallel rows of aligned bores, there being nine bores in each row. Each bore of group B also carries a perforating punch hereinafter described. The perforations in group B denote in figures the amount to be paid on the check, which as shown in Fig. 9 is \$1,469.75, and the two rows of bores at the right hand end of group B may be used to denote "cents".

Above group A, at the left hand side of the check C is a group D consisting of a row of nine aligned bores with a second bore beside the first, second, and last bore of such row; the perforations of group D are used to denote the day of the month on which the check was made, which as shown in Fig. 9 is the 20th day.

At the opposite end of check C is a group E consisting of two rows of aligned bores, each row containing six bores, said group E being used to denote the number of letters in the name of the maker of the check, which as shown in Fig. 9 is eighteen.

Between groups B and E, at the upper end of check C is a group F of three rows of aligned bores, each row having four bores, and group F being used to denote the month in which the check was drawn, which as shown in Fig. 9 is the eighth month.

Below group F is a group G consisting of two rows of aligned bores, each row containing five bores, and in addition perforations on each side of the first bores in each row, said group G being used to denote the number of letters in the name of the payee of the check, which as shown in Fig. 9 is fifteen.

As shown in Fig. 9 the check C has marked thereon the name of the payee "John Boyce Newman"; also the amount of the check \$1,469.75; also the name of the maker "Daniel Weston Hewitt"; and the date of the check "August 20th, 1926". The location of the perforations in the check denote in group A the initials of the payee and maker of the check; in group B the amount of the check; in group D the day of the month on which the check was made; in group F the month in which the check was drawn; group E the number of letters in the name of the maker of the check; group G the number of letters in the name of the payee. The check may contain consecutively numbered blocks for writing in the names of the payee and maker so that the number of letters in their names may be readily seen at a glance.

In each of the bores of groups B, D, E, F, G, is placed a perforating disk 5 (Fig. 4) above plate 2, said disk 5 having a stem 5^a extending above the plate 4, said stem 5^a having a collar 5^b thereon engaging the perforation in plate 4. A spring 5^c is interposed between the collar 5^b and a washer plate 3^x im-

mediately above the plate 3, said spring normally urging the stem 5^a upwardly. Upon the top of stem 5^a is a head 5^d having a figure such as "1", "2", "3", etc. marked upon its upper face. By depressing head 5^d disk 5 will 70 perforate the check C interposed between plates 2 and 3 of the machine.

The heads 5^d of the plungers in the various groups are marked as follows, (see Fig. 10):—The horizontal rows of heads 5^d in 75 group B reading from the top downward are marked 6, 7, 8, 9, 1, 5, 4, 3, 2, respectively.

In group D the horizontal rows are marked 11, 22, 3, 4, 5, 6, 7, 8, 90 respectively. In group E the heads in the horizontal rows are marked 12, 12, 34, 56, 78, 90 respectively. In group F the heads in the horizontal rows are marked 1, 4, 7, 10; 2, 5, 8, 11; 3, 6, 9, 12, respectively; and in group G the heads in the horizontal rows are marked 1; 1, 3, 5, 7, 9; 2, 4, 6, 8, 0; 2 respectively.

For groups B, D, E, F, G, the respective positions of the perforations are fixed and the same perforations in every check indicate the same figure. For group A, however, the perforations for the same letters vary according to the setting of the tapes 6 hereinafter described.

In the bores of group A are perforating disks 7 (Fig. 3) similar to disks 5, and having their lower ends adapted for cutting perforations in the check C when the check is interposed between the plates 2 and 3 and the disks depressed. Disks 7 are provided with rods 7^a which extend above the upper face of plate 3, the rods 7^a passing through perforations in a washer plate 3^x mounted immediately above the top of plate 3. Top plate 4 fixedly mounted upon the top of plate 3 is also provided with perforations 4^a corresponding in spacing with that of the bores in plate 3. On the upper end of rods 7^a are heads 7^b which make a sliding fit in the perforations 4^a of plate 4, and the rods 7^a are normally held in raised position with their heads 7^b substantially flush with the surface of plate 4 by means of spring 7 interposed between the heads 7^b and the washer plate 3^x.

At each end of the machine adjacent one edge thereof are mounted drums 8 and 9 around which run the tapes 6 which carry the plungers for depressing perforating disks 7. Four such tapes 6 are shown, but more or less tapes may be used. Drums 8 for each tape at one end of the machine are merely idler drums; the drum 9 at the other end of the machine is mounted on a shaft 9^a which extends through the front face of the casing and is provided with a knob 9^b by which the drum may be rotated to collectively adjust the tapes 6 with respect to the heads 7^b of disks 7. Upon drum 9 as shown in Figs. 7 and 8 are four tape collars 9^c which are normally keyed to the drum 9 by means of pins 9^d whereby rotation of the drum 9 will also simultane- 130

ously rotate the collars 9^c. Mounted upon the shaft 9^a of drum 9 is a dial 9^e which is provided with thirty-one divisions or graduations which may be consecutively numbered, 5 but are preferably numbered as follows: 1, 6, 11, 2, 5, 10, 4, 8, 3, 7, 9, 16, 20, 15, 18, 13, 17, 14, 19, 12, 21, 26, 24, 28, 22, 27, 23, 30, 29, 25, and 31, a zero point 1^s being marked on the front face of the casing adjacent the dial. 10 Tapes 6 are preferably endless steel tapes which are perforated and drawn as at 6^a (Fig. 3) and each tape has at least twenty-six such perforations; the perforations 6^a corresponding in spacing with the bores in the plates 2 and 3, and the perforations 6^a in the tapes 6 being adapted to register with the said bores of group A when the tapes are in adjusted position. In the bores 6^a of tapes 6 are mounted plungers 6^b having heads 6^c on their upper ends, the plungers being normally held in raised position by means of springs 6^d interposed between the heads 6^c and the tapes 6. The plungers 6^b being thereby movable with the tapes. On the head 6^c of each plunger is 20 stamped or impressed one letter of the alphabet. As shown in Figure 1 the lettering for each row of the tapes 6 is different, for instance, the lettering of the inner row commences with "G", that of the next row with the letter "O", the third row with the letter "T" and the outer row with the letter "S".

Hence when the tapes 6 are adjusted so that plungers 6^b directly overlie the heads 7^b of plungers 7, and when the heads 6^c are depressed the plungers 7 will likewise be depressed and a corresponding perforation punched in the check C.

As shown in Fig. 1 the dial 9^e is set so that the code word S A F E, corresponding with the 20th day of the month (see setting of dial 9^e) appears opposite the arrow 1^x on the casing of the machine. Each day of the month a new system or combination of code words is desired, and hence it is necessary to 40 shift the tapes 6 by manipulating the knob 9^b so that dial 9^e will read the particular day of the month thereby moving all of the tapes in the same direction to bring the new code word opposite the arrow 1^x. In order, 45 however, to provide additional variations in the code word, means are provided whereby the tapes may be operated independently instead of simultaneously or collectively.

As shown in Figs. 6, 7, and 8, a depressible 50 lock 10 is mounted on the top of the machine adjacent the drum 9; said lock 10 having a bolt 10^a adapted to enter into slots 1^y or 1^z (Fig. 8) in the side of the machine, and said lock 10 being normally held in raised position by means of a spring 10^b. Extending 55 through drum 9 is an axially movable rod 10^c having pairs of spaced collars 10^d thereon adjacent each tape collar 9^c. In the bore of drum 9 are pivotally mounted bell crank 60 levers 10^e having their legs bifurcated, one

leg engaging rod 10^c between its respective pair of spaced collars 10^d, and the other leg engaging spaced collars 9^c on its respective pin 9^d which locks collar 9^c to drum 9. By inserting a key in the lock 10 the bolt 10^a may 70 be withdrawn from the upper slot 1^y and inserted in the lower slot 1^z. By lowering the lock 10 an axial movement is imparted to the rod 10^c by means of a lever 10^f engaging a slot 10^g in lock 10, said lever being mounted on a shaft 10^h. A second lever 10^j on shaft 10^h having an opening 10^k therein for the passage of rod 10^c engages between spaced collars 10^l, 10^m on rod 10^c whereby as the lock 10 is lowered the rod 10^c will be moved and will 80 actuate the bell crank levers 10^e to withdraw pins 9^d out of engagement with the collars 9^c. In such position the collars 9^c may be rotated by hand or by suitable adjusting devices hereinafter described. 85

In the base below and parallel with the drum 9 is a rocker shaft 11, carrying a pair of C-shaped arms 11^a which are keyed thereto and in the arms 11^a are mounted shafts 11^b (four being shown) which lie adjacent the periphery of the collars 9^c. Each shaft 11^b carries a roller 11^c which is adapted to frictionally engage a cog 9^x on its respective collar 9^c when the arms 11^a are rocked to bring the same into engagement rollers 11^c 95 being preferably faced with soft rubber or leather. One such shaft 11^b with its roller 11^c is provided with each of the collars 9^c and the outer ends of shafts 11^b extend through the front face of the machine and 100 are provided with knobs 11^d whereby the shafts 11^b may be separately rotated to adjust the individual collars 9^c and thereby adjust the individual tapes 6.

Preferably the tapes 6 are provided with 105 a series of perforations 6^x which engage teeth 9^z on the periphery of collars 9^c so that the movement of the tapes 6 will be positive with respect to the movement of the collars 9^c. Fig. 5 shows another form of tape 6 with 110 which plungers are not necessary, the letters of the alphabet being marked beside holes in the tape, and a sharp instrument used to operate the perforating disks through such holes. Shaft 11 is provided with an arm 11^e 115 projecting in the opposite direction from the arms 11^a which lever 11^e underlies a pivoted lever 12 which is depressed through suitable link mechanism 12^a, 12^b, and bell crank 12^c by the depression of the lock 10 120 simultaneously with the withdrawal of the pins 9^b from the collars 9^c.

By adjusting the knobs 11^d when lock 10 is depressed any desired combination of letters 125 to form any code word of four letters can be brought opposite the arrow 1^x on the upper face of the casing.

It can be easily understood that unless all banks using these machines were able to issue 130 checks according to some secret code known

only to themselves which checks can be readily verified by any bank belonging to the same group (viz, the American Bankers Association) a machine might be purchased from the manufacturers by anyone and checks fraudulently issued thereon. To eliminate this danger a code word is selected by the head of the association of banks and communicated to all banks using these machines with instructions that until further notice the code word, viz: "SAFE" is to be used, and that all machines used by all the banks in the association are to be set so that the letters S-A-F-E read downwardly in vertical alignment opposite the arrow 1^s on, for instance, the twentieth day of the month. (See Figs. 1 and 10.) After the machines are to set a different combination of letters will appear opposite the arrow 1^s for each day of the month as the dial 9^e is turned each day to bring the particular day of the month opposite arrow 1^s.

In operation the blank check is placed in the machine between plates 2 and 3 and cams 1^d rotated to lock the check between said plates. The dial 9^e is then rotated to bring the day of the month (viz, 20th) opposite arrow 1^s. The plungers of the various groups are then depressed to perforate the check; the three inner tapes 6 being used to denote the initials of the payee, and the outer tape 6 being used to denote the initials of the maker. In reading the check a keyboard (Fig. 10) is used based on the code word "S A F E" for the twentieth day of the month and the location of the perforations in group A would give the desired initials. Obviously if a keyboard based on any other code word were used in reading the check the initials displayed in group A would not correspond with those on the actual check, and payment on the check would be refused.

I do not limit my invention to the exact form shown in the drawings, for obviously changes may be made therein within the scope of the appended claims.

I claim:

1. In a check perforating machine, a plurality of perforating disks and a movable endless tape carrying keys for operating said disks.

2. In a check perforating machine, a plurality of perforating disks; a plurality of operators for said disks; and means for shifting the operators comprising a pair of drums endless bands carrying the operators and adapted to run around said drums; and means for rotating one of said drums.

3. In a check perforating machine, a plurality of perforating disks; a plurality of operators for said disks; means for collectively shifting the operators; and means for individually shifting the operators.

4. In a machine as set forth in claim 3, said means for collectively shifting the operators

comprising a pair of drums, endless bands carrying the operators and adapted to run around said drums; and means for rotating one of said drums to shift the bands.

5. In a check perforating machine, a plurality of rows of reciprocable perforating disks; a row of operators for each row of disks; means for collectively shifting the rows of operators; and means for individually shifting the rows of operators. 70 75

6. In a machine as set forth in claim 5, said individual shifting means comprising a pair of drums for each row, endless bands each having one run adapted to overlie a row of said disks and carrying the operators, said bands being adapted to run around said drums; and means for rotating one drum of each pair. 80

7. In a check perforating machine, a plurality of rows reciprocable perforating disks; a row of operators for each row of disks; means for collectively shifting the rows of operators; means for individually shifting the rows of operators; and means for disengaging one of said means when the other is in action. 85

8. In a check perforating machine; a row of perforating disks; drums mounted opposite the ends of said row; a flexible band running around the drums and having one run overlying the disks; a plurality of operators for depressing said disks carried by said band; and means for rotating one of said drums. 95

9. In a check perforating machine; a plurality of rows of perforating disks; pairs of drums mounted in the machine opposite the ends of each row; flexible bands running around each pair of drums each having one run overlying a row of disks; a plurality of operators for depressing said disks carried by each band; and means for collectively and individually shifting said bands. 100 105

10. In a check perforating machine as set forth in claim 9; said means comprising a cylinder adapted to be rotated, the drums at one end of the machine being rotatably mounted on said cylinder; radially movable bolts in the cylinder adapted when projecting to lock the drums to the cylinder; and means for simultaneously actuating said bolts. 110

11. In a check perforating machine; a plurality of rows of perforating disks; a rotatable cylinder mounted in the frame at one end of the rows; drums mounted opposite the ends of each row; the drums at the cylinder end of the machine being rotatably mounted on said cylinder; endless bands adapted to run around each pair of drums; a plurality of plungers for depressing said disks carried by each band; movable bolts in the cylinder adapted when projected to lock the drums to the cylinder; and means for simultaneously actuating the bolts. 120 125

12. In a check perforating machine as set

- forth in claim 11, said bolt actuating means comprising a lock member reciprocably mounted in the frame; a rod axially movable in said cylinder; bell-crank levers 5 mounted in the cylinder each having one leg engaged with a bolt and the other leg engaged with the rod; and link connections between the lock member and rod whereby when the lock member is depressed the bolts 10 will be retracted.
13. In a check perforating machine; a plurality of rows of perforating disks; a rotatable cylinder mounted in the frame at one end of the rows; drums mounted opposite the ends 15 of each row; the drums at the cylinder end of the machine being rotatably mounted on said cylinder; flexible bands adapted to run around each pair of drums, each band having one run overlying a row of disks; a plurality of plungers for depressing said disks carried by each band; radially movable bolts in the cylinder adapted when projected to lock the drums to the cylinder; means for simultaneously actuating the bolts; and means operated by the bolt actuating means whereby 20 when the bolts are retracted the individual drums may be rotated on the cylinder.
14. In a check perforating machine as set forth in claim 13, said bolt actuating means 25 comprising a lock member reciprocably mounted in the frame; a rod axially movable in said cylinder; bell-crank levers mounted in the cylinder each having one leg engaged with a bolt and the other leg engaged with the rod; and link connections between the lock member and rod whereby when the lock member is in one position the bolts will be projected, and when the member is in the other 35 position the bolts will be retracted.
15. In a check perforating machine as set forth in claim 13, said means for individually rotating the drums comprising a rocker shaft parallel with the cylinder; link connections 40
- for rocking the shaft by and with the bolt actuating means; arcuate arms carried by said shaft; a plurality of spindles carried by said arms; each spindle having a disk thereon adapted when the arms are rocked to contact with the respective drum on said cylinder; and knobs on said spindles. 45
16. In a check perforating machine; a plurality of rows of perforating disks; a rotatable cylinder mounted in the frame at one end of the rows; drums mounted opposite the ends of each row; the drums at the cylinder end of the machine being rotatably mounted on said cylinder; endless bands adapted to run around each pair of drums; a plurality of plungers on each band for depressing said disks; radially movable bolts in the cylinder 50 adapted when projected to lock the drums to the cylinder; a lock member reciprocably mounted in the frame; a rod axially movable in said cylinder; bell-crank levers mounted in the cylinder each having one leg engaged with a bolt and the other leg engaged with the rod; link connections between the lock member and rod whereby when the lock member is moved the bolts will be simultaneously moved; and means operated by the lock member whereby 55 when the latter is depressed the individual drums may be rotated on the cylinder. 60
17. In a check perforating machine as set forth in claim 16, said means for individually rotating the drums comprising a rocker shaft 75 parallel with the cylinder; link connections for rocking the shaft by and with the movement of the lock member; arcuate arms carried by said shaft; a plurality of spindles carried by said arms; each spindle having a disk 80 thereon adapted when the arms are rocked to contact with its respective drum on said cylinder; and hand knobs for rotating spindles. 85

In testimony that I claim the foregoing as my own, I affix my signature.

JOHN H. DAVIS.
